[57] CLAIM

The ornamental design for an automotive trash compactor, as shown and described.

DESCRIPTION

FIG. 1 is a perspective view of an automotive trash compactor shown in an open condition of use showing my new design;

FIG. 2 is a left side view thereof, shown with the switch and wires omitted for ease of illustration;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a front view of the switch portion thereof shown with the compactor housing and wires omitted for ease of illustration;

FIG. 9 is a rear view thereof;

FIG. 10 is a left side view thereof; and the right side view is a mirror image thereof; and,

FIG. 11 is a top view thereof; and the bottom view is a mirror image thereof.
